UNITED STATES PATENT OFFICE.

WALTER P. GEHRETT, OF SAN FRANCISCO, CALIFORNIA, ASSIGNOR TO REMINGTON TYPEWRITER COMPANY, OF ILION, NEW YORK, A CORPORATION OF NEW YORK.

TYPEWRITING MACHINE.

Application filed July 29, 1920. Serial No. 399,698.

To all whom it may concern:

Be it known that I, WALTER P. GEHRETT, citizen of the United States, and resident of San Francisco, in the county of San Francisco and State of California, have invented certain new and useful Improvements in Typewriting Machines, of which the following is a specification.

My invention relates to typewriting machines, and it has for its principal object to provide an improved means whereby the main or carriage-driving spring can be attached to and detached from the machine more conveniently than heretofore.

It is a further object of the invention to provide a container for the driving spring which may be conveniently carried around by the repairman independently of the spring drum and to so construct the parts as that when it is necessary for the repairman to substitute for a broken or damaged spring a new spring, it is merely essential for the repairman to detach the old spring with its container from within the spring drum and to replace it with a new spring and its container, whereas formerly it was customary for the repairman to carry with him not only the new spring but also the entire spring drum and parts attached thereto.

To the above ends my invention consists in certain features of construction, and combinations and arrangements of parts, all of which will be set forth herein and particularly pointed out in the claims.

In the accompanying drawings,

Figure 1 is a front to rear vertical sectional view of a portion of a Remington No. 10 typewriter, the section being taken centrally of the spring drum.

Figure 2 is a front view in section on the line $\alpha-\alpha$ of Figure 1.

Figure 3 is a perspective view of the drum and of the main spring and its detachable container, both of said parts being removed from the machine and separated from each other.

The main frame of the No. 10 Remington typewriter includes a top plate 1 and a bracket 2 which hangs down from the rear part of said top plate to which it is secured by two screws 3, only one of which is shown in the drawing. The bracket 2 includes a boss or hub-like part 4 in which

is journaled the fore and aft extending shaft 5 of the spring drum. Said shaft has a middle part 6 of relatively large diameter about which the driving spring 7 is coiled, and a rear end part 8 of less diameter and, forward of the enlarged part 6, another part 10 of reduced diameter and which is journaled in the boss 4 of the bracket 2. Forward of the part 10 is a further reduced and squared part 11, and the extreme front end 12 of the shaft is round and threaded. A ratchet wheel 13 and a cup-shaped washer or head 14 are mounted on the squared part 11 and are clamped by a nut 15 against the shoulder at the end of the part 10 of the shaft. The cup-shaped washer 14 is slotted, as indicated at 16, so that any flat object can be inserted screw-driver fashion to put the spring 7 under tension, the tension of the spring being maintained by a double pawl 17 pivoted on the screw 18 passing into a boss 20 of the bracket 2. These parts have not been fully shown or described for the reason that they are familiar to persons skilled in the art, having been for a good while in use on the Remington machine.

The rotary carriage-driving or spring drum 21 having a connecting tape 22 wound partway about its periphery, is here shown as being in the nature of a wheel made of sheet metal and "staked" to a hub 23 which is journaled on the rear reduced part 8 of the shaft 5. A beveled gear 24 is journaled on the rear part of the hub 23 and meshes with a beveled gear 25 to drive the ribbon spools of the machine. The gear 24 has integral therewith a ratchet wheel 26 engaged by a pawl 27 pivoted at 28 to the driving drum 21 so as to feed the ribbon in only one direction.

The above parts have been described or briefly referred to merely because they are portions of the Remington typewriter with which the driving spring is immediately associated. As far as my invention is concerned these associated devices can be of any suitable sort.

It will be understood that the drum 21 includes a web-part 30, here shown as cut out to make four spokes, and a cylindrical flange-part 31 on which latter the tape 22 is wound. Posts 32 are riveted to the web-part 30 and extend parallel with the shaft

5. In the present instance I have shown two such posts diametrically opposite to each other. The spring 7 is enclosed in a container 33, which as here shown is in the 5 form of a sheet metal ring with a hook 34 struck inward therefrom and to which the outer end of the spring 7 is connected, said spring being perforated and caught over the hook in the usual manner. The ring 10 33 is flanged preferably at one edge thereof, the flange part, as shown in the present instance, consisting of two ears 35, each notched or perforated at 36. If the parts be held in the relative positions shown in Fig. 3 15 the container 33 can be slipped axially into the drum 21 between the posts 32, the spring 7 encircling the part 6 of the shaft 5 and the posts 32 entering the perforations 36, whereupon the spring container 20 33 will be mounted in and interlocked with the drum or wheel 21, and by the device described independent rotary movement of the ring with respect to the wheel will be prevented, though the two may turn together 25 during the travel of the carriage.

The container can be secured in the drum against accidental axial displacement in any suitable way. The means shown in the present instance consists of a cover plate 30 37 (Fig. 1) laid flat against the ends of the posts 32 and secured to said posts by screws 38 screwed into the interiorly threaded ends of the posts. In the Remington machine, as heretofore constructed, there 35 have been posts like the posts 32 and a cover plate 37 secured in position in the manner described; but the spring has been connected directly with the drum or wheel 21 and not mounted in a separate detachable 40 container. In the present instance I have shown the perforations 36 as round holes but it will readily be perceived that the ears could be cut off at the broken lines 40 (Fig. 2) if preferred, leaving only notches to engage the posts 32.

The inner end of the spring is perforated as shown at 41 (Fig. 3) to engage a pin 42 projecting from the shaft 5. This form of connection is such that when the inner 50 end of the spring is slipped over the shaft if the pin does not happen to go into the hole at first it will be drawn into it by relative turning of the parts.

As shown in the present instance, the 55 flange 31 of the drum 21 is at one point cut and bent inward, forming a tongue 43 and a slot 44 through which the tape 22 passes to the inside of the drum. To the inner end of the tape is attached a ring 45 60 and a screw 46 passes through a hole in the flange 31 and through the ring and is thread-

ed into an ear 47 bent up out of the web of the wheel.

It has heretofore been the practice in manufacturing these machines to mount the 65 driving spring in the drum or wheel 21 and in assembling the machine this drum and spring formed a unit. Also repairmen, who have to go about to the various offices where the machines are in use, were required to 70 carry with them the entire drum 21 with the spring mounted in it in case they were called upon to replace a broken driving spring. By the use of the present improvement 75 springs are much more conveniently stored in the small containers 33, and one of these containers with a new spring 7 mounted in it makes a much more convenient unit for the repairman to carry about with him. Besides this new construction simplifies and 80 cheapens repair work with respect to the driving springs.

Various changes may be made without departing from my invention.

What I claim and desire to secure by Letters Patent is:

1. In a typewriting machine, the combination with the carriage-driving drum or wheel having posts therein, of a unit structure consisting of a driving spring and a 90 container ring in which said spring is mounted, said ring being adapted to be inserted in said wheel between said posts and having flanged parts for engaging said posts to hold the container in place. 95

2. In a typewriting machine, the combination with a carriage-driving drum or wheel having posts therein, of a unit structure consisting of a driving spring and a container ring in which said spring is mounted, said 100 ring being adapted to be inserted in said wheel between said posts and having flanged parts for engaging such posts; and a cover plate mounted on the ends of said posts to retain said container and spring 105 against accidental displacement axially.

3. In a typewriting machine, the combination with a carriage driving drum including a web-portion having parts projecting therefrom parallel with the axis of the drum, 110 of a spring container adapted to be inserted in the drum between said projecting parts and having flanged parts adapted to engage said projecting parts of the drum. 115

Signed at the city of San Francisco, in the county of San Francisco and State of California, this 20th day of July, A. D. 1920.

WALTER P. GEHRETT.
